John H. McReady

UNITED STATES PATENT OFFICE.

CHARLES A. PERSONS, OF WORCESTER, MASSACHUSETTS.

SADDLE.

1,306,622.

Specification of Letters Patent. Patented June 10, 1919.

Application filed January 22, 1917. Serial No. 143,618.

To all whom it may concern:

Be it known that I, CHARLES A. PERSONS, a citizen of the United States, residing at Worcester, in the county of Worcester and 5 State of Massachusetts, have invented certain Improvements in Saddles, of which the following description, in connection with the accompanying drawings, is a specification, like reference characters on the drawings indicating like parts in the several 10 figures.

This invention relates to saddles of the character used on bicycles, motorcycles and similar vehicles.

15 The invention aims to devise a saddle of this character which can be economically manufactured, shall be thoroughly substantial in construction and will have the resiliency which is necessary to give it the 20 easy riding qualities desired in devices of this character. The invention is particularly concerned with the spring construction for supporting the rear portion of the seat of the saddle.

25 The invention will be readily understood from the following description, reference being made to the accompanying drawings in which,

30 Figure 1 is a side elevation, partly in cross section, showing a saddle embodying this invention;

Fig. 2 is a rear elevation, partly in cross section, of the saddle shown in Fig. 1;

Fig. 3 is a side elevation showing a modified spring construction;

Fig. 4 is a cross sectional view showing the manner in which the springs are clamped to the main truss or support of the saddle, and

40 Fig. 5 is a side elevation showing a modification.

The saddle shown comprises a seat 2, a cantle plate 4 supporting the rear portion of the seat and a truss 6 consisting of two members lying side by side and forming the main support for the other parts of the saddle.

45 For the purpose of supporting the cantle plate, two pairs of springs are interposed between it and the truss 6. One pair 50 of these springs consists of two coiled tension springs indicated, respectively, at 7 and 8, the upper ends of these spring being secured to the rear ends of the truss members by bolts 9 and 10, respectively, and their 55 lower ends being bolted to the lower ends of

a U-shaped bridge piece 12 which is clamped to the cantle plate by means of two clips or straps 14 and two bolts indicated, respectively, at 15 and 16. A brace 18 clamped to the rear ends of the truss members 6 by 60 means of the bolts 9 and 10 holds these members properly spaced apart.

The construction so far described is substantially like that heretofore used in saddles which I have manufactured and shown 65 in certain of my prior patents. The spring support for the pommel portion of the saddle here shown is also like that shown in my Patent No. 1,174,177, granted March 7, 1916.

According to the present invention a pair 70 of torsion springs, indicated, respectively, at 19 and 20, is interposed between the cantle plate and the truss 6 and they coöperate with the tension springs 7 and 8 to support the rear portion of the seat. The construction of these torsion springs is clearly shown in Figs. 1 and 2, from which it will be seen that the legs of each spring extend forward beyond the coiled part of the spring in directions substantially parallel to each 80 other, the upper leg having a horizontal eye formed at its end through which one of the bolts 15 or 16 extends and clamps it to the cantle plate, while the lower leg of each spring has a vertical eye formed at its end 85 through which one of the bolts 9 or 10 extends and secures it to the truss 6.

In order to reduce the liability of breaking the torsion springs and for the purpose 90 also of adding to the easy riding qualities of the saddle, I prefer to secure one leg, at least, of each of the torsion springs to the part with which it is connected in such a manner that it can pivot or rock relatively to its point of connection. Fig. 4 shows the 95 construction here employed for the purpose of accomplishing this object. As clearly shown in this figure, the eye at the end of the lower leg of the spring 19 is clamped to the truss member 6 by the bolt 9, but a 100 spacing collar 22 is employed to keep the bolt from binding the eye. That is, this collar has a tubular part encircling the bolt 9 and is itself encircled by the eye of the spring 19, and it also has a radial flange which separates the eye from the eye of the brace 18. The tubular portion of this collar is of a length greater than the diameter of the wire from which the spring is made so that when 105 the nut on the bolt 19 is turned up to clamp 110

all the parts together, the collar 22 prevents any binding of the eye of the spring. A similar construction, of course, is employed to clamp the spring 20 to the truss member 6.

- 5 By using a spring construction of this character I am enabled to support the saddle on four relatively light springs whose tension or resistance to the downward movement of the saddle increases more gradually 10 than would the tension of a single pair of springs of sufficient strength to support the same weight. A more resilient and easier riding saddle thus is produced.

Fig. 3 shows the left hand set of springs 15 only of slightly modified construction. The spring 19 used in this embodiment of the invention has long eyes *a* and *b* formed, respectively, in the upper and lower horizontal legs or end portions of the spring. The 20 bolts 15 and 9 extend respectively through these eyes *a* and *b*, as in the arrangement shown in Figs. 1 and 2, and this construction thus permits the rider to adjust the tension of the springs 19 and 20 to suit his own 25 weight or individual preferences. In order to make this adjustment it is merely necessary to loosen the bolts 15 somewhat and slide the springs 19 and 20 forward or backward to reduce or increase the effective 30 lengths of the legs of the springs, as desired, and then tighten the bolts again.

It is obvious that various constructions 35 of torsion springs may be used and that the manner of connecting them to the supporting truss and to the seat, or some member that supports the seat, may be varied considerably without departing from the spirit or scope of this invention. In Fig. 5 a slight modification of the arrangement 40 shown in Figs. 1 and 2 is illustrated in which the upper leg of the torsion spring 19 instead of being bolted to the cantle plate is provided with a vertical eye that

encircles the bridge piece 12 at a point between the clip 14 and the vertical leg of the 45 bridge piece. Various other means for connecting the torsion spring to its point of support may be used while still maintaining the essential characteristics and features of this invention. 50

What is claimed as new, is:—

1. In a saddle of the character described, the combination with a seat, a cantle plate for said seat and a supporting truss, of two torsion springs each having two legs extending in the same direction beyond the coiled portion of the spring, the legs of each of said springs being secured respectively to said truss and cantle plate, and two coiled springs connected with said support and 60 cantle plate and coöperating with said torsion springs to support said seat, the securing means for one leg of each of said torsion springs being constructed and arranged to enable said leg to turn relatively to the 65 part to which it is secured, said torsion springs and their securing means being constructed and arranged to enable the torsion springs to be adjusted to vary their tension.

2. In a saddle of the character described, 70 the combination with a seat, a cantle plate for said seat and a supporting truss, of two vertically arranged torsion springs each having two legs extending forwardly beyond the coiled portion of the spring, the 75 legs of each of said springs being secured, respectively, to said truss and cantle plate, two coiled tension springs supported at their upper ends by said truss, and a U-shaped bridge member secured to said cantle plate 80 and having the lower ends of its legs secured, respectively, to the lower ends of said tension springs.

In testimony whereof I have signed my name to this specification.

CHARLES A. PERSONS.
